UNITED STATES PATENT OFFICE.

PHILIP W. MOORE, OF EVANSTON, ILLINOIS, ASSIGNOR TO THE P. & M. CO., OF CHICAGO,
ILLINOIS, A CORPORATION OF ILLINOIS.

ANTICREEPER.

1,175,653.

Specification of Letters Patent. Patented Mar. 14, 1916.

Application filed March 29, 1915. Serial No. 17,616.

To all whom it may concern:

Be it known that I, PHILIP W. MOORE, a citizen of the United States, residing at Evanston, in the county of Cook and State 5 of Illinois, have invented new and useful Improvements in Anticreepers, of which the following is a full, clear, concise, and exact description, reference being had to the accompanying drawing, forming a part of 10 this specification.

My invention relates to improvements in anti-creepers for railroad rails.

The main object of the invention is to provide a light, simple and inexpensive anti- 15 creeper which may be readily and securely applied to the rail base and which is effective in resisting creeping.

Other objects are to provide an improved anti-creeper of the type which fits only one 20 side of the rail base; to provide an anti-creeper of this type having improved means for holding it to the rail base; to provide an anti-creeper which does not work loose after 25 being applied but which may be readily removed if desired; and to provide an anti-creeper of this character having a pin adapted to have a driving fit within an 30 opening in the rail.

In the accompanying drawings, I have 35 illustrated a simple and practical embodiment of the invention which represents a further development of the device disclosed in my Patent 1,140,345, issued May 18th, 1915, Serial Number 859,289, filed August 31, 1914, renewed April 3rd, 1915, Serial Number 18,920.

Referring to the drawings: Figure 1 is a rear view of the anti-creeper showing the rail in section. Fig. 2 is a side view thereof 40 showing a portion of the rail in side elevation. Fig. 3 is a perspective view of the anti-creeper.

In Figs. 1 and 2, the rail 1 is shown resting on one of the usual cross-ties 2. The 45 anti-creeper or rail anchor 3 is applied to one side only of the rail base. It consists largely of a jaw having upper and lower members 4, 5 respectively, the angle of which is such as to insure a firm frictional 50 hold on the base flange of the rail when the anti-creeper is driven onto said flange, for example, to the position shown in Fig. 1 in which said anti-creeper may be assumed to have been driven from the right. When the 55 anti-creeper has been driven toward the left

as far as possible, the vertical extension 6 thereof is brought very close to, but not quite in contact with, the vertical web of the rail base. It could be in contact with said web but for variations in the individual 60 anti-creepers which necessarily arise in casting them in large numbers, and for other reasons, as a result of which it is desirable to provide said clearance to insure the driving of the anti-creeper as far onto the rail 65 as it will go before the vertical extension meets the vertical web of the rail and prevents the anti-creeper from being driven far enough to spring the jaw somewhat and insure a firm grip of the base flange. Said 70 anti-creeper which is made preferably of malleable iron or suitable equivalent material, is reinforced adjacent to the small end of the jaw by a heavy flange 7 whereby said 75 springing action may take place without breakage or without permanent distortion of the jaw. The casting has a depending flange 8 formed integrally therewith and arranged preferably beneath the opening of the jaw, said flange being adapted to bear 80 against the cross-tie 2 to transmit the creeping thrust thereto, being suitably reinforced for this purpose by a flange or bracket 9.

In order to maintain the anti-creeper or anchor in the effective position to which it 85 has been driven, I provide a suitable pin or rivet 10 which is driven through an opening in the vertical extension 6. The projecting end of said pin tapers somewhat and the pin itself is of such diameter as to insure a driving fit within an opening which is drilled 90 for the purpose in the vertical web of the rail. Said opening is comparatively small and therefore not objectionable, being usually about one-fourth the diameter of the 95 usual holes drilled for the bolts at the rail joints. Hence, the expense of drilling and the damage to the rail are a minimum. The pin fits tightly within the opening in the extension 6 and hence may be inserted therein before the rail anchors are shipped. However, the preferred method is to ship the pin 100 separately. The rail anchor may then be applied to the rail base and the opening therein used as a templet to guide the drill which drills the hole in the web of the rail. The pin is thereafter driven through both 105 aligned openings.

In prior instances where rail anchors have 110 been secured in place by pins passing

through openings in the web of the rail, the pins have been smaller than the opening, and have been provided with cotter pins or other positive locking devices to prevent withdrawal of said pins. This produces rattling and tends to loosen the device due to the resulting vibration. In certain of said prior devices, the pin is of malleable iron constituting an integral part of the anchor, whereby said pin may be damaged in handling and in shipment, and whereby it would wear away rapidly if driven in and out of the opening more than once, so that it would not maintain a driving fit even if such fit were intended originally, which is not the case. My rail anchor may be taken from the rail and reapplied if desired, the driving fit of the pin being maintained even if driven in and out several times, and if the pin eventually is worn enough to destroy the driving fit, a new pin may be readily substituted. The expense of the pin is a small item; and since the casting may be reapplied to a rail as often as desired without impairing its qualities, the life of the anchor is extended indefinitely by simply renewing the pins, although where the anchor is once applied and left in position, no renewals of any kind are necessary for indefinite periods.

It is obvious that various changes may be made in the structure described, without departing from the spirit of the invention. For example, the opening in the rail need not necessarily be located in the vertical web, but may be otherwise located. The anchor need not necessarily be made as a casting, but of other material than cast-metal. I desire, therefore, to cover in the appended claims whatever modified structures fall within the scope of the invention.

Having thus described my invention what I claim as new and desire to secure by Letters Patent of the United States is:

1. The combination with a railroad rail, having an opening therein, of an anti-creeper applied thereto, and provided with a pin of such size as to have a driving fit in said opening, to aid in securing said rail anchor in place.

2. The combination with a railroad rail having an opening in the vertical web thereof, of an anti-creeper having a jaw which grips one flange of the rail base, a pin carried thereby adapted to have a driving fit in said opening whereby said anti-creeper

is held to the rail and means engaging a cross-tie to transmit the creeping thrust thereto.

3. An anti-creeper comprising a single jaw for gripping one side of a rail base, a tie-abutting flange and a projection arranged to have a driving fit in an opening in the web of the rail.

4. A rail anchor comprising a single jaw arranged to fit over one side of a rail base, and a pin carried thereby adapted to have a driving fit in an opening in said rail, said pin being removable from said rail anchor whereby it may be replaced when necessary.

5. A rail anchor comprising an integral casting in the form of a jaw for gripping one side only of a rail base, a downwardly extending flange arranged directly below the opening of said jaw, means for reinforcing the small part of said jaw, an integral extension on the upper part of said jaw, and a tapering steel rivet passing through an opening therein.

6. The combination with a railroad rail having a small opening in the vertical web thereof, of an anti-creeper which fits one side of the rail base and has an extension arranged parallel and adjacent to said web, and having an opening therein in alignment with the opening in said web and a pin passing through both of said openings and serving by its frictional contact with said web to maintain itself in position and secure the rail anchor in place.

7. The combination with a railroad rail having an opening therein, of an anti-creeper which maintains a frictional hold thereon and has an opening therein aligned with said first opening and a pin fitting within the second opening and adapted to have a driving fit in said first opening to lock said anti-creeper in place.

8. The combination with a railroad rail of an anti-creeper applied thereto, and a pin fitting within an opening in said rail, said pin being independent of said anti-creeper structurally, but co-operating therewith to maintain it on the rail base.

In witness whereof, I have hereunto subscribed my name in the presence of two witnesses.

PHILIP W. MOORE.
